Primary Examiner — John Windmuller*Assistant Examiner* — Luqman McNeil(74) Attorney, Agent, or Firm — Mark D. Miller(57) CLAIM

I claim the ornamental design for pants with utility pocket, as shown and described.

DESCRIPTION

FIG. 1 is a front perspective view of a two-pocket embodiment of pants with utility pocket showing my new design;

FIG. 2 is a left side view thereof;

FIG. 3 is a right side view thereof;

FIG. 4 is a rear view thereof;

FIG. 5 is a top left perspective view thereof; and

FIG. 6 is a top right perspective view thereof.

FIG. 7 is a front perspective view of a one-pocket embodiment of pants with utility pocket showing my new design;

FIG. 8 is a left side view thereof;

FIG. 9 is a right side view thereof;

FIG. 10 is a rear view thereof;

FIG. 11 is a top left perspective view thereof; and,

FIG. 12 is a top right perspective view thereof.

The broken lines on the interior and exterior indicate stitching.

1 Claim, 10 Drawing Sheets---
